[57] **CLAIM**

The ornamental design for a playground and activity structure, as shown and described.

DESCRIPTION

FIG. 1 is a top left front perspective view of a playground and activity structure showing our new design. The broken lines are for illustrative purposes only and form no part of the claimed design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a top plan view thereof.

The broken lines are for illustrative purposes only and form no part of the claimed design.

FIG. 2

FIG. 4

FIG. 6
